D20-20

EX

OR D 20,460

D 20460

Design No. 20,460, dated January 6, 1891.

UNITED STATES PATENT OFFICE.

LOUIS SOLON GROUT, OF CHICAGO, ILLINOIS.

DESIGN FOR A WATCH-MAKER'S SIGN.

SPECIFICATION forming part of Design No. 20,460, dated January 6, 1891.

Application filed November 10, 1890. Serial No. 370,960. Term of patent 7 years.

To all whom it may concern:

Be it known that I, LOUIS SOLON GROUT, a citizen of the United States of America, residing at Chicago, in the county of Cook and State of Illinois, have invented and produced a new and original Design for Watch-Maker's Signs, of which the following is a specification, reference being had therein to the accompanying drawing.

- 10 The drawing represents a face view of the sign, the leading feature of which is a circular border having a rope-molding to its inner and outer edge and having blank shields for applying words for advertising, this circular border forming the frame for a sign being the representation of a watch with six (more or less) star-points to its periphery and being provided with an acorn-shaped hanger surrounding a serrated knob representing the 20 winding-knob of a watch.

A denotes the inner plate, being the repre-

sentation of a watch with star-points *c* to its periphery. D is the circular border to plate A, having an inner and outer rope-molding *d* and *e* and having blank shields *f* for lettering, intermediate of which the ring border may be ornamented by cross-lining or otherwise. To its upper end the ring border D has the hanger G, representing the ear of a stem-winding watch, which is acorn-shaped and surrounds the knob *g*, being the representation of the winding-knob.

What I claim is—

The design for a watch-maker's sign herein shown and described.

In testimony whereof I affix my signature in presence of two witnesses.

L. SOLON GROUT.

Witnesses:

WM. H. LOTZ,

OTTO LUEBKERT.
